UNITED STATES PATENT OFFICE

2,005,266

SLOW-OPENING VALVE

William A. Ray, San Francisco, Calif., assignor
to General Controls Co., a corporation of California

Application November 13, 1933, Serial No. 697,797

4 Claims. (Cl. 137—139)

This invention relates to a control valve, particularly a valve of the slow opening type utilized to control gas flow to a furnace.

It is an object of the invention to provide a control valve, the speed of operation of which can be controlled by means independent of the valve structure.

Another object of the invention is to provide an improved valve of the character described.

Another object of the invention is to provide a gas flow control system enabling furnace operations to be improved. In controlling gas flow to a furnace, however, it is desirable that, when the furnace is started into operation, the rate of gas flow to the burner be increased gradually to a maximum. This is because with a cold furnace draft conditions often are very unfavorable. By starting with a small gas flow the proper draft is created and, by the time the valve has opened to permit full gas flow, the furnace or fire box is under the proper draft. The valve and system have been used with success on natural gas fired furnaces and although not limited to this use, will be described in this connection.

A further object of the invention is to provide a valve which is of a simple and rugged construction, particularly adapted for manufacture.

The invention possesses numerous other advantageous features and objects, some of which, together with the foregoing, will appear at length in the following wherein the present preferred form of my invention is disclosed.

In the drawing, the single view shows a valve, partly in section, in conjunction with other diagrammed parts of my system.

A valve body structure 6 is included between gas inlet line 7 and gas outlet line 8 which extends to burner 9 in furnace 10. A member 11 is screwed into the body 6 to provide a valve seat and a passage through which flow can occur from the inlet to the outlet. Cooperatively adjacent to seat member 11 is annular member 12 which is movable to and fro, to seat against seat 11 or permit flow. This annular member is made of rubber or other suitable material and is carried by piston 13 to which it is secured by a plug 15 screwed into the piston. Piston 12 has a loose fit in cylinder 14 which is provided as a skirt on flange 16 positioned and secured on the body 6 by studs (not shown).

A diaphragm chamber formed by lower section 17 and upper section 18 is provided, section 17 being screwed into flange 16. The two sections are held together with a flexible diaphragm 19 be-

tween, by screws 20. The diaphragm 19 is secured between plates 21 and 22 by a screw 23 which engages rod 24. The rod 24 is engaged with piston 13 by a pin 26 so that the diaphragm can move the piston and the valve member 12 carried thereby. The diaphragm and its chamber are in effect a cylinder and piston.

Gas from the inlet is admitted to diaphragm chamber 16 by passing between the piston 13 and cylinder 14 and then through restricted passages 10 27 in the section 17. Gas passes to the diaphragm section 18 through restricted passages 28 in the rod 24 and another passage 29 in the screw 23. To protect against material collecting in the section 17 entering the passages 28, a skirt 31 is positioned on the end of rod 24 and the plate 22. This shields the passages if the valve, when not in use, is placed on its side.

A plug 32 is screwed into section 18 and provides a seat for a valve member 33 movable to control flow out of section 18, through outlet 34 and pipe 36 which extends to the furnace. The valve member 33 is operated by a suitable device as the solenoid 37, which, when actuated, serves to control opening and closing movement of member 12 with respect to valve seat 11.

With valve member 33 in that position shown in the drawing, fluid pressure on opposite sides of the diaphragm equalizes. However, the pressure can also act on piston 13 and urges that member to rest on valve seat 11 and hold the valve closed. As soon as valve member 33 is raised by the solenoid, pressure in section 18 drops so that the higher pressure in the section 17 can move the diaphragm upwardly to raise piston 13. However, this raising movement is at a slow rate due to the restricted passage about the piston and through conduits 27.

A valve 38 is included in line 36, usually being screwed into outlet 34. This valve is adjustable, 40 usually manually, so that the rate of opening of the main flow valve can be varied, valve 38 controlling the rate of leakage out of chamber 18, and, consequently, the rapidity with which the diaphragm rises when valve member 33 is raised. 45 Passages 28 and 29 to the chamber 18 restrict flow past the diaphragm to the extent necessary to ensure that the diaphragm can raise the piston 13 against the pressure thereon while permitting sufficient flow to take place to ensure that the valve will not open quickly.

The line 36 extends to the furnace 10 so that the small amount which passes therethrough is burned. It is only when the main valve is open and primary flow occurs through lines 7 and 8

that the secondary control flow takes place in chamber, an outlet from said other side of said chamber, and means for controlling fluid passage through said outlet.

To ensure that the valve can be opened even if the device 37 can not be actuated to raise valve member 33, threaded rod 39 is extended through plug 41 in the valve body to engage plug 15. When cap 42 is removed from the plug, the rod can be turned so as to engage the plug and raise the valve off the seat.

10 I claim:

1. A device of the character described comprising a valve body including a valve seat and a cylinder in said body, a piston fitting loosely in said cylinder and carrying a valve member cooperating with said seat, a diaphragm chamber mounted on said body and including a flexible member, a member connecting said flexible member and said piston, a conduit for passing fluid leaking past said piston to one side of said flexible member in said chamber, and a passage to the other side of said flexible member in said diaphragm chamber.

2. A device of the character described comprising a valve body including a valve seat and a cylinder in said body, a piston fitting loosely in said cylinder and carrying a valve member cooperating with said seat, a diaphragm chamber mounted on said body and including a flexible member, a member connecting said flexible member and said piston, a conduit for passing fluid leaking past said piston to one side of said flexible member in said chamber, a passage to the other side of said flexible member in said diaphragm

5 chamber, an outlet from said other side of said

chamber, and means for controlling fluid passage

through said outlet.

10 3. A device of the character described comprising a valve body including a valve seat and a cylinder in said body, a piston fitting loosely in said cylinder and carrying a valve member cooperating with said seat, a diaphragm chamber mounted on said body and including a flexible member, a member connecting said flexible member and said piston, a conduit for passing fluid leaking past said piston to one side of said flexible member in said chamber, a passage to the other side of said flexible member in said diaphragm chamber, an outlet from said other side of said chamber, means for controlling fluid passage through said outlet, and means for varying the rate of fluid passage through said outlet.

15 4. A device of the character described comprising a valve body including a valve seat and a cylinder in said body, a piston fitting loosely in said cylinder and carrying a valve member cooperating with said seat, a diaphragm chamber mounted on said body and including a flexible member, a member connecting said flexible member and said piston, a conduit for passing fluid leaking past said piston to one side of said flexible member in said chamber, a passage to the other side of said flexible member in said diaphragm chamber, and a skirt partially surrounding said 20 passage.
